DESIGN FOR A CARD-GAME TABLE TOP

Carl M. Graves, Oakwood, Ohio

Application December 19, 1933, Serial No. 50,127

Term of patent 7 years

To all whom it may concern:

Be it known that I, CARL M. GRAVES, a citizen of the United States, residing in the city of Oakwood, in the county of Montgomery and State of Ohio, have invented a new, original, and ornamental Design for a Card-Game Table Top, of which the following is a specification, reference being had to the accompanying drawing, forming part hereof.

I claim:

The ornamental design for a card-game table top, as shown.

CARL M. GRAVES.
